UNITED STATES PATENT OFFICE

JOSEPH GRANAT, OF SAN FRANCISCO, CALIFORNIA

DESIGN FOR A FINGER RING

Application filed November 19, 1930. Serial No. 37,703. Term of patent 7 years.

To all whom it may concern:

Be it known that I, JOSEPH GRANAT, a citizen of the United States of America, residing at San Francisco, county of San Francisco, and State of California, have invented a new, original, and ornamental Design for Finger Rings, of which the following is a specification, reference being had to the accompanying drawing, forming a part thereof.

The figure is a perspective view of my design both sides of the ring being identical.

I claim:—

The ornamental design for a finger ring substantially as shown and described.

JOSEPH GRANAT.
